UNITED STATES PATENT OFFICE.

HERBERT B. NICHOLS, OF NEW YORK, N. Y.

NASAL DOUCHE.

1,248,891.

Specification of Letters Patent. Patented Dec. 4, 1917.

Application filed June 18, 1917. Serial No. 175,306.

To all whom it may concern:

Be it known that I, HERBERT B. NICHOLS, a citizen of the United States, and a resident of the borough of Manhattan of the city of New York, county and State of New York, have invented certain new and useful Improvements in Nasal Douches, of which the following is a specification, reference being had to the accompanying drawing, which 10 forms a part hereof.

The invention seeks to provide a nasal douche adapted to cleanse the nasal passages more effectually than has been possible heretofore with nasal douches now in use.

15 It consists of the construction hereinafter set forth.

In the accompanying drawing forming part of this specification, the invention is shown in its preferred form.

20 Referring now to the drawing, 1 is an ordinary douche bag from which leads a rubber tube 2 attached to the lower end of the glass tube 3. 4 is a nozzle adapted to be inserted in the left nostril. The nozzle 4 is connected with the upper end of a short 25 length of rubber tubing 5, the lower end of which is connected with the upper end of the glass tube 3. 6 is a well known form of valve clamp by means of which the tube

30 2 may be closed and opened. Tubes 2, 3 and 5 and the nozzle 4 constitute an inlet tube for the injection of the cleansing liquid, generally water, into the nasal passages through the left nostril. Associated with the inlet 35 tube is an outlet tube designed to be simultaneously connected with the right nostril.

As shown in the drawing, the outlet tube consists of a section of rubber tubing 7 connected to the lower end of a glass tube 8 40 which, in turn, is connected with the nozzle 9 through the intermediation of the short section of rubber tubing 10. The cleansing liquid injected into the left nostril passes out through the right nostril and thence 45 through the outlet tube, carrying with it mucus and other foreign matter. The outlet tube acts in the manner of the long leg of a siphon, creating a suction within the nasal passages thereby more effectually 50 cleansing them than has heretofore been possible with a mere injection appliance such as has comprised nasal douches in general use. The outlet tube not only creates a suction within the outer nasal passages 55 through which the cleansing liquid passes

but also acts upon the sinuses connecting with the inner nasal passages and withdraws from them mucus and other foreign matter upon which an ordinary injection douche has little or no effect.

60 In the preferred arrangement, the inlet and outlet tubes are united by a connecting member 11 having a handle 12. As shown in the drawing, the connecting member consists of a block of suitable material bored to 65 receive the glass tubes 3 and 8. The flexible sections 5 and 10 enable the nozzles 4 and 9 to be adjusted relatively to suit varying conditions.

65 In operating the douche the nozzles 4 and 9 are adjusted within the nostrils and the liquid is allowed to flow from the douche bag into the left nostril, discharging through the outlet tube. It may be found desirable to temporarily close the inlet tube after the 70 nasal passages have been filled with the cleansing fluid in order to increase the initial efficiency of the outlet tube.

75 While I prefer that the outlet tube shall act as the long leg of a siphon in effecting 80 its purpose, it would not be a departure from my invention to arrange the outlet tube so as to act upon some other principle so long as it acts as a suction tube.

85 What I claim is:

1. A nasal douche comprising an inlet tube and a separate suction outlet tube, said tubes being adapted to be operatively connected with both nostrils simultaneously.

2. A nasal douche comprising separate inlet and outlet tubes adapted to be operatively connected with both nostrils simultaneously, and a member connecting the tubes together near their upper ends, said tubes having flexible portions above said member. 95

3. A nasal douche comprising separate inlet and outlet tubes adapted to be operatively connected with both nostrils simultaneously, and a member connecting the tubes together near their upper ends, said tubes 100 having flexible portions above and below said member.

4. A nasal douche comprising an inlet tube and a separate siphon-acting outlet tube, said tubes being adapted to be operatively connected with both nostrils simultaneously. 105

This specification signed this 13th day of June A. D. 1917.

HERBERT B. NICHOLS.
